Primary Examiner — Lauren D McVey

(57) **CLAIM**

The ornamental design for an automatic bookmark, as shown and described.

DESCRIPTION

FIG. 1 is a front, right side and top perspective view of an automatic bookmark, showing my new design;
FIG. 2 is a rear, left side and top perspective view thereof;
FIG. 3 is a rear, left side and bottom perspective view thereof;

FIG. 4 is a front elevation view thereof;

FIG. 5 is a rear elevation view thereof;

FIG. 6 is an enlarged left side elevation view thereof;

FIG. 7 is an enlarged right side elevation view thereof;

FIG. 8 is a top plan view thereof; and,

FIG. 9 is a bottom plan view thereof.

The broken lines in the figures illustrate portions of the automatic bookmark that form no part of the claimed design.

1 Claim, 9 Drawing Sheets
